UNITED STATES PATENT OFFICE.

FRANZ TROSIENER, OF DÜSSELDORF, GERMANY.

CONTRIVANCE FOR SATURATING LIQUIDS WITH GAS.

942,115.

Specification of Letters Patent.

Patented Dec. 7, 1909.

Application filed August 10, 1909. Serial No. 512,121.

To all whom it may concern:

Be it known that I, FRANZ TROSIENER, a citizen of the German Empire, residing at Düsseldorf, in the Province of Rhineland and Kingdom of Prussia, Germany, have invented new and useful Improvements in Contrivances for Saturating Liquids with Gas, of which the following is a specification.

10 The present invention contemplates a contrivance for saturating liquids with gas, in which a measuring faucet of well known construction is used, the body of which is connected not only with the piping for feeding on the liquid to be saturated and the exit for the saturated liquid, but also with a mixing vessel and a carbonic acid-bottle, and the plug of which is provided with several chambers, to be brought in conjunction with 15 the supply and the escape. On turning the plug from the one into the other operative position the chamber actually filled with the liquid to be saturated, is moved past the inlet for the gas, and in its final position it is 20 brought in connection with mixing vessel, into which the liquid under pressure is driven under atomization, after which, owing to the tilting of the whole of the contrivance, the now saturated liquid is 25 turned toward the chamber for being evacuated from this, after having turned the plug into the subsequent operative position.

The drawing, in which similar letters refer to similar parts throughout the several 30 views, shows one form of embodiment of the contrivance.

Figure 1 represents it in longitudinal section, and Fig. 2 is a section taken on the line A to B of the Fig. 1, while Fig. 3 is 35 illustrative of the contrivance in a partial side-view.

The contrivance consists of the vessel *a* and of the casing or body *b* of the cock, connected by means of sockets *d*, fit to be kept 40 in screw-engagement, and supported by means of a lever *f* pivoted at *e* on a table or a wall or in similar ways. The plug of the cock is formed by four chambers, *k'*, *k²*, *k³*, *k⁴*, each of which carries an aperture *l* for the 45 admission or the exit respectively of the liquid as well as the further apertures *m* and *n*. The body of the cock is connected by means of a pipe *g* with a carbonic acid-bottle or the like and with a vessel *a* by a pipe 50 *d*. The pipe *d* has provided therein a brush 55

p above which a serrate rail or another suitable device is arranged. The supporting plate for the brush has pivotally affixed thereto a flap valve *q* which conveys the liquid running from the body *b* to the vessel *a* past the brush, which, however, when by the turning of the contrivance at the lever *f* the vessel *a* is moved in upward direction, swings 60 backward, so that the impregnated liquid, without entering into contact with the brush, 65 is free to flow back into the body *b*.

When the plug is in the position shown in Fig. 1, the chamber *k'* is being filled with liquid. When turning the plug through an angle of 90° the chamber gets connected to 70 the pipe-socket *d* and simultaneously it is moved with its aperture *m* past the supply-pipe *g* for the carbonic acid, so that carbonic acid enters into the chamber *k'* pressing the liquid therein against the brush *p* 75 and into the vessel *a* during which operation the liquid is atomized or separated by means of the brush and of the serrate rail into a number of small particles and thereby is 80 intimately mixed up with the carbonic acid. 85 The aperture *m* is arranged in such a way, that at the turning of the plug of the cock, the connection between the chamber and the inlet *g* for carbonic acid be checked prior to the coming of the plug of the cock into its 90 actual final position. The liquid in the vessel *a* is caused to return to the chamber *k* by turning the device at the lever *f*. The carbonic acid contained in the said chamber 95 may, when the liquid flows back into the chamber, pass over to the vessel *a* through the aperture *n* and the pipe *o*.

For drawing away impregnated liquid it is only required to turn the plug of the cock through a further angle of 90°, in which arrangement the opening *l* of the chamber enters into connection with the outlet socket. 95

For preventing the plug to be turned in the wrong direction, *i. e.* to the right, under reference to the drawing, a ratchet-wheel *r*, as shown in Fig. 3, and a pawl *s*, engaging with this, may be provided at the body *b*. Further the handle may carry a spring-actuated pin *t*, which after each quarter of a rotation of the plug clicks into a recess in the 100 top of the body of the cock, so that the plug can be moved farther from this position only by expending a somewhat greater force. The object of this arrangement is to prevent, that the plug of the cock be moved in- 105 110

advertently too far, *i. e.* beyond the actual operative position.

I claim:—

1. A device of the character described, comprising a mixing vessel, a casing connected thereto, a chambered apertured plug rotatable within the casing, a liquid pipe and a gas pipe adapted to communicate with the plug, an atomizer intermediate mixing vessel and casing, and means for pivotally supporting the vessel and casing.

2. A device of the character described, comprising a mixing vessel, a casing connected thereto, a chambered apertured plug rotatable within the casing, a liquid pipe and a gas pipe adapted to communicate with the plug, a brush and a flap valve intermediate mixing vessel and casing, and means

for pivotally supporting the vessel and casing.

20

3. A device of the character described, comprising a mixing vessel, a casing connected thereto, a chambered apertured plug rotatable within the casing, a liquid pipe and a gas pipe adapted to communicate with the plug, a brush, a serrated rail and a flap valve intermediate mixing vessel and casing, and means for pivotally supporting the vessel and casing.

25

Signed by me at Cologne this 27th day 30 of July, 1909.

FRANZ TROSIENER.
